UNITED STATES PATENT OFFICE.

FREDERICK C. WEBER, OF CHICAGO, ILLINOIS.

APPARATUS FOR APPLYING LIQUID FUEL TO BLAST-FURNACES.

SPECIFICATION forming part of Letters Patent No. 325,292, dated September 1, 1885.
Application filed January 10, 1885. (No model.)

To all whom it may concern:

Be it known that I, FREDERICK C. WEBER, a citizen of the United States, residing at Chicago, in the county of Cook and State of Illinois, have invented a new and useful Improvement in Apparatus for Applying Liquid Fuel to Blast-Furnaces, of which the following is a specification:

The particular object of my invention is to provide means for introducing petroleum as a fuel and reducing agent for blast-furnaces, as described in my application filed June 23, 1884; but it is also applicable to any other class of furnaces in which petroleum or other liquid fuel is used; and the invention consists, essentially, of a reservoir for containing petroleum supplies, service-pipes having devices whereby the flow of petroleum may be regulated, and devices for properly connecting the supply-pipes with the blast-pipes or tuyeres, as hereinafter described.

In the accompanying drawings, Figure 1 is a central vertical section of a blast-furnace and of my apparatus for applying petroleum thereto, and is especially designed to show the relative positions of my apparatus to the furnace. Fig. 2 is a central vertical section of a part of the furnace, taken through one of the tuyeres with its blast-pipe and through one of my petroleum-burners with its supply-pipe, regulating-valves, &c. Fig. 3 is a rear elevation of one of the petroleum-supply pipes with its stop-cock and mechanism for regulating the petroleum-flow. Fig. 4 is a rear elevation in cross-section of a tuyere and its burner, taken in line 4 4 of Fig. 2. Fig. 5 is an end view of such tuyere and burner; and Fig. 6 is taken in cross-section in line 6 6 of Fig. 2, and particularly shows the manner in which the burner lies in the tuyere.

A represents a section of a smelting-furnace, this furnace being provided with a main water-pipe, B, having branches b b, a blast-pipe, C, having branches c c, and tuyeres D. Each tuyere may have an opening in its lower wall, through which the end of the burner is inserted.

The burner consists of a pipe, E, surrounded by a water-jacket, F, and may be held in suitable shoulders or lugs formed either upon said burner or upon the tuyere. The burner E is provided at its lower end with a suitable

mouth or orifices, through which the petroleum is admitted to the blast-chamber.

I prefer to make the water-jacket F in two horizontal compartments, which may be formed by casting a dividing-rib, f, so as to bridge the space between the inner wall of the water-jacket and the outer wall of the burner. This water-jacket F surrounds the burner to the point where the latter is connected to a feed-pipe, G, and is separate from the water-jacket used below this point. I prefer to connect this feed-pipe with a circular underground main, H, which in turn is connected with a main, I, also underground. The main I is provided with a stop-cock, Q, by means of which the petroleum-flow can be regulated or stopped. The main I leads from a feed-tank, J, the level of the petroleum in which is maintained by float j. This level can be maintained at such height as to furnish the required head of oil, and by maintaining a constant head maintains an even and regular flow, and this head also overcomes any pressure within the furnace. The supply-tank J is connected with a storage-tank, K, which latter contains the petroleum-supply.

The supply-pipe G and burner E are connected by a coupling, g. Below this coupling, 80 pipe G is provided with a stop-cock, L, which may be an ordinary plug-valve with an aperture of any suitable form. This plug is provided with a lever, M, which is made to swing in front of an arc-dial, O, the latter being 85 marked with a graduated scale. By means of this lever and arc-dial the amount of petroleum admitted through the burner may be accurately regulated or determined.

A ball-valve, P, is placed within the feed-pipe just above the stop-cock, and as the head of oil allows the petroleum to flow up to a stated pressure within the furnace this ball-valve automatically checks all flow in excess of this pressure.

The part which I have denominated the "burner" (marked E in the drawings) consists of a pipe which is cylindrical in form up to the point where it enters the tuyere, and at this point the form of the pipe changes from the cylindrical into the oval. The burner terminates in a mouth or orifices, N. The castings which form the walls of the mouth or orifices of the burner may be cored out, and

through these chambers thus formed the water flows from the lower to the upper compartment, thus cooling the burner and the walls of the orifices. It is evident that the shape or

5 form of the burner and its orifices may be considerably varied without affecting the results sought to be accomplished by them. All that is necessary to be observed in the construction of these burners, as well as of their surrounding water-jackets, is that the construction be such as to permit a regular flow and avoid the possibility of melting. I have described but one burner; but it will of course be understood that each tuyere has its burner, and 15 each burner receives its petroleum-supply from the circular main H through pipes similar to pipes G.

I contemplate locating the storage and feed tanks at such a distance from the furnace that 20 all danger of fire and explosion of the petroleum will be avoided. The orifices and supply-pipes should of course be surrounded with water-jackets, so as to avoid danger from fire.

The petroleum is caused to flow through the 25 orifices of the burner by its own weight, and can be held above the point where the burners enter the tuyeres. As already stated, this level is maintained by the use of a float, and this float is so arranged as to operate a valve 30 in the pipe leading from the storage to the feed tank. In order to maintain a uniform level of the petroleum through the stop-cock L, the retardation of the flow of liquid caused by the friction in the service-pipes should be 35 compensated for by making said pipes of increased diameter according to their length.

By means of the above apparatus a predetermined quantity of petroleum may be supplied to the blast in each of the tuyeres.

40 I have described my apparatus particularly as used in connection with blast-furnaces; but it will of course be understood that it is equally applicable to any other kind of furnaces in which petroleum or other liquid fuel 45 is used; for by regulating the flow of the pe-

troleum, as above described, complete burning may be obtained and the heat-giving power of the petroleum fully utilized.

I claim—

1. The combination, with the tuyere of a blast or other furnace, of petroleum tanks or reservoirs having floats to maintain a level or head of oil, service-pipes having devices whereby the flow of the petroleum may be regulated, supply-pipes having valves or other regulating devices for feeding the petroleum with the blast, and protecting water-jackets, substantially as described. 50

2. The combination, with the tuyere of a blast or other furnace, of petroleum tanks or reservoirs having floats to maintain a level or head of oil, service-pipes having devices whereby the flow of petroleum may be regulated, supply-pipes having valves or other regulating devices for feeding the petroleum 65 with the blast, protecting water-jackets, and safety-valves for preventing explosions, substantially as described.

3. The combination, with the tuyere of a blast or other furnace, of petroleum tanks or reservoirs having floats to maintain a level or head of oil, service-pipes having devices whereby the flow of the petroleum may be regulated, supply-pipes having valves or other regulating devices for feeding the petroleum 70 with the blast, protecting water-jackets, and means for regulating and determining the petroleum-flow, substantially as described.

4. The combination, with the tuyere of a blast or other furnace, of petroleum tanks or reservoirs having floats to maintain a level or head of oil, service-pipes I, having stop-cock Q, supply-pipe E, having valve L, lever M, and arc-dial O, a burner, protecting water-jacket F, and ball-valve P, substantially as 85 described. 80

FREDERICK C. WEBER.
